DISPLAY STAND

Morris L. Wurman, Melrose Park, Pa., assignor to Bayuk Cigars Incorporated, Philadelphia, Pa., a corporation of Maryland

Filed Nov. 2, 1960, Ser. No. 62,707

Term of patent 14 years

(Cl. D80—10)

FIG. 1.

FIG. 2.

FIG. 4.

FIG. 5.

I claim:

The ornamental design for a display stand, as shown.
